UNITED STATES PATENT OFFICE

JOHN H. WILHELM, OF ROCKAWAY BEACH, LONG ISLAND, NEW YORK, ASSIGNOR TO
MARKON MANUFACTURING CO. INC., OF NEW YORK, N. Y., A CORPORATION OF NEW
YORK

MEANS FOR FITTING EYE SETS IN DOLL HEADS

Application filed February 5, 1927. Serial No. 166,036.

This invention relates to a means for fitting eye sets in doll heads, and particularly to a fazing tool for smoothing and dressing the spaced eye openings or sockets of doll heads and similar toys.

In the manufacture of doll heads the eye sockets are crudely formed at the time the heads are molded, and such smoothing and dressing of said sockets as may be required to enable them to properly receive and form an accurate fit with the eyeballs may be readily accomplished by the present implement or tool, and in order that the tool may be particularly adaptable for this use in doll heads which have restricted neck openings through which the tool may be inserted, as well as for other purposes, it is an object of the present invention to so construct the tool that its parts are readily adjustable. A further object is to so design the tool as to embody an extremely simple means for driving the fazing elements in appropriate directions while at the same time facilitating quick and easy adjustment thereof. A further object is to provide simple, practical and efficient means for insuring accuracy of operation of the tool within a doll head or the like.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment of the invention:—

Fig. 1 is a side elevational view of a fazing tool constructed in accordance with this invention.

Fig. 2 is an enlarged horizontal sectional view taken substantially upon the plane of line II-II of Fig. 1.

Fig. 3 is a further enlarged vertical sec-

tional view taken substantially upon the plane of line III-III of Fig. 2.

Fig. 4 is a view similar to that seen in Fig. 3 but showing the fazing elements in a different adjusted position.

Fig. 5 is a horizontal detail sectional view taken substantially upon the plane of line V-V of Fig. 1.

Fig. 6 is a side elevational view illustrating the fazing tool as it appears in connection with a device by which to insure its accuracy of position within a doll head or the like, a doll head being illustrated in heavy dotted lines.

Fig. 7 is a horizontal sectional view taken upon the plane of line VII-VII of Fig. 6, parts of the doll head being illustrated in section on said plane and the remainder of the doll head being illustrated by heavy dotted lines, and

Fig. 8 is a diagrammatic view corresponding with the central portion of Fig. 7 and illustrating the manner in which an eye set may be supported by the same parts of the doll head as previously used to locate the tool.

Referring to the drawings for describing in detail the structure illustrated therein, the reference character L indicates a suitable support, as for instance an ordinary work table or the like. To this table is rigidly connected a standard G which at its upper end is formed with a horizontal bearing 1 within which is rotatably mounted a shaft 2. A pulley or other suitable drive element 3 is connected to one end of this shaft adjacent the standard. The opposite end of the shaft projects a considerable distance beyond the standard and has a spiral gear 4 fixed to its outer end.

The standard G is formed with two vertical openings as 5 and 6 therein which define three separate lugs or ears as 7, 8 and 9 spaced apart by the openings 5 and 6.

The bearing 1 within which the shaft 2 is mounted is formed through one of these ears as 7.

The intermediate ear, as 8, provides a bearing as 10 within which is rotatably received one end of a sleeve 11 surrounding the shaft,

and the last ear as 9 provides a bearing as 12 within which is rotatably received a second sleeve as 13 surrounding the first sleeve.

The sleeve 11 projects into the space 5 and there carries a collar 14 which is fixed to said sleeve and which provides a stud 15 projecting laterally of the sleeve and of the standard.

The sleeve 13 projects into the space 6 and there carries a collar 16 which is fixed to said sleeve 13 and which provides a stud 17 projecting laterally of the sleeve 13 and of the standard.

Pivottally mounted upon the intermediate ear 8, as by means of a pivot pin or screw 18 is a plate 19 having two slots therethrough as 20 and 21, the former receiving the projecting portion of the stud 15 and the latter receiving the projecting portion of the stud 17. The slots and studs being arranged at opposite sides of the pivot 18 it follows that swinging movement of the plate about said pivot 18 will cause a rocking movement of the two sleeves 11 and 13 simultaneously in opposite directions and to an extent determined by the extent of swinging movement of the plate.

Depending from the plate 19 is an arm 22 arranged to move between a pair of stops 23 and 24, and continuing downwardly from the lower end of said arm, is preferably a foot operable lever 25 having a foot portion H thereon, said foot lever being preferably pivotally connected with the arm as by means of a pivot pin 26 and being adapted to be held in a selected position of adjustment with respect to said arm by means of a clamp bolt as 27 carried by the foot lever and movable within an arcuate slot 28 provided at the lower end of the arm.

The stops 23 and 24 are each adjustable within an arcuate slot 29 provided within a portion as 30 of the standard, the stops being fitted with clamp nuts as 31 and 32 respectively by means of which they may be held in any position of adjustment.

Any suitable means may be provided for temporarily retaining the arm 22 in one or both of its extreme positions. In the instance illustrated one of the stops, as the stop 24, is shown to be provided with a stud 33 and the arm 22 is formed with a co-operative socket 34 adapted to receive the stud when the arm is in a selected position.

Each of the stops may be provided with similar studs if desired, and it will be understood that there is sufficient flexibility between the parts, either by reason of the flexible material of the arm, or the part 30 of the standard, or by reason of resiliency of the stud 33, or otherwise, to permit the easy movement of the arm, by a snap action, into and out of engaging relation with the stud or studs.

Each of the sleeves 11 and 13 which sur-

round the shaft 2 continue to adjacent the outer end of said shaft and each is there formed to provide bearings as 35 and 36 respectively for rotatably receiving short spindles 37 and 38.

Each of these spindles carries a spiral gear as 39 and 40 respectively the teeth of which stand in constant mesh with the teeth of the gear 4, being disposed at opposite sides of said gear 4. The axes of the spindles 37 and 38 and gears 39 and 40 are transverse to the length of the shaft 2 and sleeves 11 and 13, and it follows therefore that the diagonal disposition of the teeth of the three gears readily enables rotary adjustment of the sleeves about the shaft, by means of the arm 22 and its foot lever, the adjustment being accompanied simply by a slight rotary movement of the spindles 37 and 38 as the diagonal teeth of the gears 39 and 40 slide longitudinally through the diagonal teeth of the gear 4.

The shaft 2 may be continuously driven, by means of pulley 3, and the spindles be thereby continuously rotated during this adjusting operation without in any way affecting, or being affected by, the adjustment.

At the upper ends of the spindles are fixed the brazing elements proper as 41 and 42, and it is important to note that the spiral gears 4, 39 and 40 not only provide the convenient and adjustable gear connection with shaft 2 as above referred to but they also co-operate to drive the spindles, and hence the brazing elements 41 and 42 in opposite directions, as indicated by the arrows in Fig. 2, which is highly desirable in order that the tendency of one brazing element to rotate the piece of work, or doll head, in one direction will be counter-acted by tendency in the opposite direction of the other brazing element.

The portions as 43 and 44 which are provided at the ends of the sleeves 11 and 13 for carrying the spindles 35 and 36 are preferably shaped to form guards as 45 and 46 practically enveloping the respective gears and preventing the possibility of an operator's hand or fingers coming into objectionable contact therewith.

The tool as thus conceived is of simple, strong and substantial construction. In using it for brazing the eye sockets of doll heads, or other articles where openings are present for providing easy access of the tool to said sockets, the arm 22 may be held relatively fixed to one of its stops, and the stop may be adjusted at a given position so that the brazing elements will occupy a fixed relationship to each other without alteration during the use of the tool for repeated brazing operations.

Where, however, the tool is to be employed for brazing the eye sockets of doll heads or other articles which have restricted openings through which the tool may reach its work the foot lever may be readily and easily em-

ployed to swing the brazing elements into their most compact relation to each other for enabling their passage through the restricted opening, and thereafter for swinging the brazing elements apart and into a definite spaced relationship to each other ready to perform their brazing operation, the foot lever being swung back and forth each time the tool is inserted into a new piece of work.

In Figs. 6 and 7 is illustrated an arrangement by which to insure an accurate positioning of the brazing elements within a doll head or the like during the brazing operation. According to this suggestion it is contemplated that the doll head, or other piece of work upon which the tool is to be used shall be provided with appropriate sockets, grooves, ribs, lugs or other guide elements and that the tool shall be provided with co-operative lugs, ribs, grooves, sockets or other guide elements adapted to mate the sockets, grooves, ribs, lugs or other guide elements of the head for thereby defining a precise position of the tool with respect to the head at the time the brazers are performing their function.

In the instance illustrated the doll head shown is formed with a pair of lugs as 47 and 48 arranged intermediate the eye sockets 49 and 50 of the head and in planes at opposite sides of a straight line centrally through said eye sockets, after the manner shown and described in the co-pending application of Alexander Konoff, Serial No. 161,915.

Also in the instance illustrated the tool shown is provided with a guide element as 51 of a shape and size to fit closely to the lugs 47 and 48 and thereby serve to hold the doll head in a precise relationship with the tool while the brazers are dressing out the eye sockets.

The guide element 51 is shown as a small plate arranged between the two brazing elements 41 and 42, being of reduced width intermediate its length so as to permit movement of the brazing elements into close proximity with each other by means of the foot lever for purposes heretofore explained, and having fingers as 52—52 at its ends for straddling the lugs and thus preventing any appreciable loose play between the plate and the lugs while the brazers are at work. The fingers 52—52 in fact may be said to define grooves as 53—53 at opposite ends of the plate one for receiving each of the lugs.

In order that the brazing elements may not reach their work until the guide element 51 has properly engaged the lugs 47 and 48 the guide element is preferably mounted upon a spring support as 54 which is arranged to hold the guide element normally pressed upwardly with respect to the brazing elements and when a doll head has been telescoped over the tool and the lugs 47 and 48 thereof fitted into the grooves 53—53 of the

guide element or plate 51 the spring 54 will serve to hold the head elevated out of contact with the brazing elements until manual pressure has been applied by the operator against the head sufficient to flex the spring and thereby bring the eye sockets down against the brazing elements. As soon as the brazing operation has been completed and the manual pressure is relieved the spring will immediately operate to lift the head away from the brazing elements so that the head may now be readily removed from the tool.

It is noteworthy that movement of the head both downwardly into engagement with the brazing elements, and upwardly out of engagement with the brazing elements, is in a positively predetermined path, defined by the manner of mounting, and the form, of the spring 54, and that hence no injury is likely to be done the eye sockets by careless handling of the head in moving it into and out of engagement with the brazing elements.

The spring 54 is illustrated as being fixed to a sleeve 55 as by means of a screw or the like 56. The sleeve 55 encircles the sleeve 13 and is connected with the standard G so that said sleeve 55 is stationary with the standard and thus the guide element or plate 51 is held always midway between the two brazing elements 41 and 42.

Also fixed to the sleeve 55 is a guide member 57, said guide member providing an opening 58 through which the spring 54 extends, the upper wall as 59 of said opening constituting a stop to be engaged by the spring for limiting the upward movement of the spring, and the lower wall as 60 of said opening constituting a stop to limit the downward movement of the spring. The lower stop 60 is of particular importance in that in limiting the downward movement of the spring, and hence of the guide member or plate 51, it also serves to limit the downward movement of the doll head or other piece of work which engages the guide element 51 and in this way determines the limit to which the brazing elements 41 and 42 may move relatively into the work.

It will be apparent that by using the same lugs 47 and 48 as guide means by which to determine the operating position of the brazing elements for preparing the eye sockets for receiving doll eyes, or the like, as are subsequently used for guiding and supporting the eyes which are intended to fit into the brazed sockets little difficulty will be experienced in obtaining an accurate fit of the eyes.

The eye set illustrated in Fig. 8 consists of two semispherical eye members 61 and 62 carried at opposite ends of a cross rod 63, said cross rod having its mid-portion connected with an attaching member 64 which engages the lugs 47 and 48 to hold the eye set in position. A weight 65 is shown as

being connected with the eyes by means of a pair of arms 66 and 67 extending to the eyes respectively, the whole being substantially in accordance with the eye set, and its attaching means as illustrated and described in said pending application, and the eye members 61 and 62 being of course spaced apart from centre to centre the same distance as are the brazing elements 41 and 42 when said brazing elements are at work.

10 It is to be particularly noted that by the use of the tool herein shown the operation of dressing or brazing out the eye sockets is readily accomplished through the restricted neck opening of the doll head, it being unnecessary to have the head open at the top or back as has been customary heretofore.

20 As many changes could be made in this construction without departing from the scope of the invention as defined in the following claims, it is intended that all matter contained in the above description or shown in the accompanying drawings, shall be interpreted as illustrative only and not in a 25 limiting sense.

Having thus described my invention, what I claim as new and desire to secure by Letters Patent is:—

30 1. A brazing tool comprising a drive shaft, a pair of spindles arranged one at each side of said drive shaft and extending in a direction transverse to the length of said drive shaft, a pair of single gears fixed one to each of said spindles, a single gear fixed to the 35 drive shaft and in constant mesh with said first gears, supporting means for said spindles by which said spindles may be inclined toward and away from each other about a pivot coinciding substantially with the axial 40 centre of the drive shaft while maintaining mesh of said gears, and said gears all being spiral gears.

45 2. A brazing tool comprising a drive shaft, sleeves rotatable upon said drive shaft, brazing elements carried by said sleeves respectively, gears fixed to said brazing elements respectively; a gear fixed to said drive shaft having operative connection with said first 50 gears to drive the brazing elements from said drive shaft, and means engaging said sleeves by which to rotate the sleeves for thereby adjusting the brazing elements with respect to each other.

55 3. A brazing tool comprising a drive shaft, sleeves rotatable upon said drive shaft, brazing elements carried by said sleeves respectively, gears fixed to said brazing elements respectively, a gear fixed to said drive shaft having operative connection with said first 60 gears to drive the brazing elements from said drive shaft, each of said sleeves having a laterally projecting stud thereon, a member engaging said studs by which to operate said studs for rotating the sleeves and for thereby 65 adjusting the brazing elements with respect

to each other, limiting stops for said last mentioned member, and means by which said limiting stops are adjustable.

4. A brazing tool comprising a drive shaft, sleeves rotatable upon said drive shaft, brazing elements carried by said sleeves respectively, gears fixed to said brazing elements respectively, a gear fixed to said drive shaft having operative connection with said first gears to drive the brazing elements from said drive shaft, each of said sleeves having a laterally projecting stud thereon, a member engaging said studs by which to operate said studs for rotating the sleeves and for thereby adjusting the brazing elements with respect to each other, limiting stops for said last mentioned member, and means by which said member may be releasably held with respect to one of said limiting stops.

5. A tool for operating upon the eye sockets of doll heads or the like comprising a pair of elements spaced apart intended to operate upon the eye sockets respectively, means to operate said elements, and means comprised in the tool adapted to engage a co-operative part of the work to thereby guide said elements with respect to the work, said last mentioned means being of a resilient character and being arranged to normally hold the work away from said elements but by its resiliency permitting manual movement of the work into engagement with said elements.

6. A tool for operating upon the eye sockets of doll heads or the like comprising a pair of elements spaced apart intended to operate upon the eye sockets respectively, means to operate said elements, and means comprised in the tool adapted to engage a co-operative part of the work to thereby guide said elements with respect to the work, said last mentioned means being of a resilient character and being arranged to normally hold the work away from said elements but by its resiliency permitting manual movement of the work into engagement with said elements, together with stop means to determine the limit of movement of said resilient guide.

7. A tool for preparing the eye sockets of a doll head to receive the eyes of an eye set therein, where the head includes attaching means to which the eye set may be connected, said tool having parts to operate upon said eye sockets, and having another part arranged to engage the mentioned attaching means and to thereby guide to said eye sockets the parts of the tool intended to operate upon said sockets.

8. A tool for preparing the spaced eye sockets of a doll head to receive the spaced eyes of an eye set therein, where the head includes a pair of lugs stationary with respect to said eye sockets adapted for use as means by which to attach the eye set, said tool including a pair of brazing elements spaced apart corresponding with the spacing apart

of the eyes of the eye set and intended to operate upon said eye sockets respectively, and said tool having a guide part adapted to engage said lugs to thereby guide the brazing elements with respect to the eye sockets.

5 9. A brazing tool comprising a drive shaft, a plurality of brazing elements, carrying members for said brazing elements respectively rotatably mounted co-axially with the drive shaft, gears fixed to said brazing elements respectively, a gear fixed to the drive shaft having operative connection with the first gears to drive the brazing elements from said drive shaft, and a pivotally mounted lever engaging said frazer carrying members to rotate said members by pivotal movement of the lever thereby moving the brazing elements with respect to each other.

10 10. A brazing tool comprising a drive shaft, 20 a pair of brazing elements, a pair of frazer carriers rotatably mounted co-axially with the drive shaft, gears fixed to the brazing elements respectively, a gear fixed to the drive shaft having operative connection with the first gears to drive the brazing elements from said drive shaft, the frazer carriers having studs thereon spaced apart in the direction of length of the drive shaft and projecting in a direction laterally of said shaft, and a lever pivotally mounted at a point intermediate said studs and connected with said studs to move the studs in opposite directions by pivotal movement of the lever, for thereby moving the brazing elements with respect 25 to each other.

30 In testimony whereof I affix my signature.
JOHN H. WILHELM.
